(57) **CLAIM**

We claim, the ornamental design for an electronic device, as shown and described.

DESCRIPTION

FIG. 1 is a top front perspective view of an electronic device showing our new design;

FIG. 2 is a front view thereof;

FIG. 3 is a rear view thereof;

FIG. 4 is a left side view thereof;

FIG. 5 is a right side view thereof;

FIG. 6 is a top view thereof; and,

FIG. 7 is a bottom view thereof.

The broken lines shown in the figures that are within the claimed surface, are immediately adjacent to the shaded areas, and define regions that are unshaded and uninterrupted by solid-line features, represent the bounds of the claim, while all other broken lines are directed to environment. The broken lines form no part of the claimed design.

The intermittently broken stripes represent a brushed metallic-looking finish.

Examples of an electronic device are: a computer; a portable or hand-held electronic device; media player such as a music, a video and/or a game player; media storage device; a personal digital assistant; and a communication device such as a cellular phone and smart phone.
